IGNITER FOR MATCHES

Reginald Arthur Tombs, Toronto, Ontario,
Canada

Application November 29, 1950, Serial No. 198,060

9 Claims. (Cl. 44—48)

1

My invention relates to improvements in igniters for ordinary matches, and it has for its primary object to provide a mechanical device by which a match can be ignited by inserting the head end in an opening and pressing it against an actuator by which the head is caused to be struck by a pointed prong and thus ignited.

The invention provides a simple and serviceable igniter for matches. It saves having to strike a match with a brushing action against an abrasive surface of a match box or the like. Furthermore it is advantageous as a safety device in that the match head is surrounded by a case while being struck and therefore any flaming particles which may incidentally fly off the match cannot do harm because of the enclosure.

The match igniter of the present invention is sturdy in construction and inexpensive to manufacture. It is well suited to be made up as a part of a match holder for use on desks and tables, for example.

The invention essentially comprises a pair of resilient members mounted upon a support one above the other and arranged so that each may be depressed independently of the other. The lower of the two resilient members carries a sharp prong which is pointed upwardly.

The upper of the two resilient members is provided with an upwardly directed opening in register with said prong. This opening is of a size to admit said prong but not the head of a match. At the upper end of said opening the upper resilient member is supplied with a surrounding seat against which the head of a match is placed to depress the upper resilient member. In the downward movement a trip plate bears on the lower resilient member to depress it and as it is depressed a cam disengages it from the trip plate to enable it to abruptly fly upwardly so that the prong will penetrate the match head to ignite the match.

A selected embodiment of the invention is illustrated in the accompanying drawing, in which

Fig. 1 is a top plan view of the invention in which the igniter is embodied in a match holder.

Fig. 2 is a vertical section on line 2—2 of Fig. 1.

Fig. 3 is a sectional view similar to Fig. 2 but showing the upper resilient member partly depressed and the trip plate engaged with the lower resilient member.

Fig. 4 is a further sectional view similar to Fig. 2 but showing the upper resilient member further depressed and also showing the lower resilient member depressed with the trip plate moved to the extreme free end of the lower resilient member for a tripping operation.

Fig. 5 is a still further sectional view similar to Fig. 2 but showing the lower resilient member released by the trip plate and rebounded upwardly to cause the prong to strike the head of the match.

Fig. 6 is an end view of the igniter, and

Fig. 7 is a perspective view of the upper resilient member.

For the purpose of illustration the igniter of the present invention is shown as mounted on the base 8 of a match holder 9. The holder is of the type which rests upon a table or other supporting surface and supplies a receptacle in which is held a number of matches, designated at 10.

The lower resilient member is indicated at 11 and the upper resilient member is indicated at 12. The members 11 and 12 are flat leaf-like strips of spring metal firmly fastened at an end to the base 8 and spaced one above the other in longitudinal alignment. The fastening and spacing means are of ordinary character and comprise the screws 13 and the distance pieces 14. Modification in the mode of attaching the members 11 and 12 by their ends to the supporting base could of course be resorted to, if so desired.

The lower member 11 is made of a stouter material than member 12 in order that it may possess greater stiffness. Near its free end 15 it is provided with a prong 16 which is sharply pointed upwardly from the top face thereof. The upper member 12 is apertured near its free end to provide a small opening 17 to admit the prong 16. The opening 17 is not large enough to admit the head of a match. The member 12 can therefore be depressed by a match placed over the opening 17 and pressed downwardly. Said opening is located to come into register with the prong 16 when the lower member 11 and the upper member 12 are brought together as in Fig. 5. Preferably the upper member 11 is provided at its free end with a flared mouth 18 at the opening 17 in order to seat the head of a match and to centre it with respect to this opening. The flared mouth is supplied by a boss 19, in the present disclosure.

The invention comprises means for causing the members 11 and 12 to come together with a snap action when the upper member is depressed by a match. The means desirably includes a trip plate 20 and a tripping cam 21. The trip plate is hinged at 22 to the free end of the upper member 11 to hang freely therefrom with its hinge-axis extending transversely. The trip plate is so located longitudinally of the upper member 11 that its lower edge will engage and rest on the free edge of the lower member 12 when the upper member is de-

50 pressed. The trip plate 20 is hinged at 22 to the free end of the upper member 11 to hang freely therefrom with its hinge-axis extending transversely. The trip plate is so located longitudinally of the upper member 11 that its lower edge will engage and rest on the free edge of the lower member 12 when the upper member is de-

pressed. A spring 23 yieldably retains the trip plate against outward movement for which purpose it is fastened to the upper member 11 and provided with an arm bent over the trip plate. Obviously, another form of spring could be used if so desired.

The tripping cam 21 is fixed on the base 8 along side of the lower member 12 and has a cam face 24 extending in upward direction and inclined inwardly beneath the trip plate. Preferably there are two such trip plates, one on each side of the upper member 12. The upper and lower members 11 and 12 along with the trip plate and the cam are enclosed in a case 25 attached to the base 8 and provided with an opening 26 in the top wall thereof to admit a match. The opening 26 may be outwardly flared or otherwise shaped to facilitate insertion of the head end of a match.

In the use of the match lighter a match is ignited by inserting the head end in the opening 26 to engage the seat 18 and then pressing the match downwardly to depress the upper member 12. In the depressional movement the trip plate 20 engages the lower member 11 and depresses it. While the lower member is being depressed the cam face 24 of the cam 21 presses the lower part of the trip plate outwardly and disengages it from the lower member. As a result the lower member rebounds upwardly and the prong strikes the match-head to ignite it. The ignited match is then withdrawn. The return movement of the upper member 12 may be assisted by a coil spring 27.

What I claim is:

1. A match igniting device comprising a base, upper and lower members supported on said base in a manner to be resiliently depressed, said members being arranged horizontally in spaced parallel relation, said upper member having an opening of a size insufficient to admit the head of a match placed against this member to depress it, a prong on said lower member and pointed upwardly, said prong being located to enter said opening for striking the match-head when said members are brought together, and actuating means operated by a depressional movement of said upper member for imparting a simultaneous lowering movement to said lower member, said actuating means being devised to abruptly release said lower member for a quick return movement during descent of said upper member.

2. A device as defined in claim 1, and in which the upper and the lower members are enclosed in a case having a top wall portion apertured at the opening in the upper member to admit a match.

3. A match igniting device comprising a base, upper and lower members supported on said base in a manner to be resiliently depressed, said members being arranged horizontally in spaced parallel relation, said upper member having an opening of a size insufficient to admit the head of a match placed against this member to depress it, a prong on said lower member and pointed upwardly, said prong being located to enter said opening for striking the match-head when said members are brought together, a trip plate on said upper member for engaging said lower member to lower it in unison with the depression of said upper member, and a cam device for disengaging said trip plate.

4. A match igniting device comprising a base, a pair of leaf-like resilient members arranged substantially horizontally one over the other in spaced parallel relation, means fastening one end

of said members to said base, the upper of said members having a free end provided at its upper side with a seat for the head of a match to enable the upper member to be depressed by the match, said seat being centrally apertured to expose at the bottom of the upper member a part of the match head, a prong on the free end of the lower of said pair of members, said prong being pointed upwardly and disposed to enter the aperture in said seat when said members are brought together, and means operated by a depressional movement of said upper member for simultaneously imparting a lowering movement to said lower member, said actuating means being devised to abruptly release said lower member for a quick return movement during descent of said upper member.

5. A match igniting device comprising a base, a pair of elongated plates of spring metal, means attaching an end of each of said plates to said base with the plates extending substantially horizontally in spaced parallel relation one above the other, the upper plate of the pair having an aperture in its free end with a surrounding seat for a match head, said aperture being of a size insufficient for the match head to pass therethrough, said seat being at the top side of the upper plate, a pointed prong on the lower plate of the pair and located to enter said aperture when the plates are brought together, a trip plate on said upper plate for depressing the lower plate when the upper plate is being depressed, and cam means for disengaging said trip plate in the depressional movement of the upper plate.

6. A device as set forth in claim 5, and in which the trip plate is hingedly attached to the upper plate to depend therefrom so that its lower part will engage the lower plate, and in which the cam means includes a cam surface disposed to disengage the trip plate from the lower plate.

7. A device as set forth in claim 5, and in which the trip plate is hingedly attached to the upper plate and spring retained to a depending position to edgewise engage the lower plate, and in which the cam means provides a cam face disposed to disengage the trip plate from the lower plate.

8. A match igniting device comprising a support, a lower resilient plate fastened on said support at an end to extend substantially in a horizontal direction, an upper resilient plate fastened on said support at an end to extend over said lower plate in spaced parallel relation, said upper plate having at its distal end an opening surrounded by an upper seating surface for the head of a match, a prong on the distal end of said lower plate, said prong being pointed upwardly and disposed to enter said opening to strike the match head when said upper and lower plates are brought together, a trip plate hingedly depending from the distal end of said upper plate to engage the distal end of said lower plate, a cam having a face for disengaging said trip plate from said lower plate, and spring means attached to said upper plate for reverting said trip plate to its depending position in which it is engaged with said distal end of the upper plate.

9. A device as set forth in claim 8, and in which a case encloses the upper plate, the lower plate, the trip plate and the cam, and in which the case has an apertured wall portion over the seating surface of the upper plate to admit a match.
